UNITED STATES PATENT OFFICE.

GEORGE W. N. YOST, OF NEW YORK, N. Y., AND CHARLES E. MERRITT, OF SPRINGFIELD, MASSACHUSETTS, ASSIGNORS TO THE YOST WRITING MACHINE COMPANY.

TYPE-WRITING MACHINE.

SPECIFICATION forming part of Letters Patent No. 450,324, dated April 14, 1891.

Application filed January 20, 1887. Serial No. 224,843. (No model.)

To all whom it may concern:

Be it known that we, GEORGE W. N. YOST and CHARLES E. MERRITT, citizens of the United States, and residents, respectively, of 5 New York city, county of New York, and State of New York, and Springfield, county of Hampden, and State of Massachusetts, have invented certain new and useful Improvements in Type-Writing Machines, of which 10 the following is a specification.

Previous to our invention the key-levers of existing type-writing machines have generally been made of various lengths and constructed on the principle of either the lever 15 of the second order or that of the third order, and have had their fulcrums arranged in a straight line transversely of the machine. To this construction and arrangement of key-levers the serious objection exists that in the 20 use of the machine the stem-keys or push-buttons of the several rows or banks which are connected with the key-levers require, according to their distances from the fulcrums of the key-levers and the points at which the 25 type-bars are connected, different applications of power and extents of movement to depress the key-levers and properly elevate the type bars or levers, to which they are joined, through the intervention of a depending connecting rod or link.

Our invention has for its main objects to overcome the above-recited objections and to provide a key-lever of such a construction that no matter whether it be connected to a 35 stem-key of one bank or that of another of the several banks which constitute the keyboard of the well-known type-writing machines it shall have always the same extent of depression and require substantially the 40 same application of power to elevate the type-bar during the operation of writing, thus rendering it easier for the operator of the machine and conducing to greater perfection in the character of the work performed.

45 To these ends and objects our invention consists, primarily, in a key-lever constructed on the principle of the compound lever, and in certain details of construction and combinations of parts, all of which will be herein- 50 after more fully described, and particularly set forth in the claims.

In the accompanying drawings, Figure 1 is a sectional view of a type-writing machine embodying our several improvements. Fig. 2 is an enlarged detail view of the compound 55 key-lever and its supporting-standard. Fig. 3 is a vertical section of the lever, taken at the line *xx* of Fig. 2. Fig. 4 is a detail elevation of the spring used in conjunction with the compound lever. Fig. 5 is an elevation 60 illustrating our improved construction of joint, a portion being broken away; and Fig. 6 is a vertical section therethrough, taken at the line *yy*.

In the several views the same parts will be 65 found indicated by the same numerals and letters of reference.

A represents the frame of the machine; B, the type-lever, type-bar, or type-carrier; C, the connecting-rod; D, the compound lever, 70 and E the finger-key, stem-key, or push-button.

The compound lever D is composed of two levers 1 and 2 of equal lengths, journaled or fulcrumed, respectively, at 3 and 4 in ears or 75 extensions of a standard or block 5, which is secured by a screw 6 to a base-plate or cross-piece 7, extending transversely of the machine and attached to the frame-work thereof near the bottom. The levers 1 and 80 2 are connected at their shorter arms, so as to work together. In the drawings the connection is shown as made by forming the shorter arm of lever 1 with an elongated hole 8 and providing the shorter arm of lever 2 85 with a projecting pin 9, which passes through and works along in said hole and serves to vibrate the lever 1 during the movements of the lever 2. The standard 5 is formed or provided with a flange or foot-piece 10 to obtain 90 a suitable bearing upon the cross-piece 7, and also with a lateral hollow or tubular extension 11, which is threaded at its lower end for the reception of the retaining-screw 6, which passes in from the bottom of the machine. 95

A light wire spring F is employed for returning the levers 1 and 2 to their normal positions after having been vibrated. This spring is preferably made in one piece and of the shape shown. About midway of its 100 length it is given substantially the shape of the letter V, as seen at 12, and from this point

on either side it is curved upwardly to the extremity, where it is formed into a hook-like portion 13. When the spring is applied to the levers, the V-shaped portion is preferably inserted within the upper end of the hollow extension 11, which is located equidistant from the fulcrums of the levers 1 and 2, and the free ends 13 hooked to the under sides or edges of the longer arms of said levers. When thus applied, the tension of the spring acts to elevate the longer arms of the levers 1 and 2 and depress their shorter arms. At the outer extremity of the longer arm of lever 2 the stem-key E is connected. In the arm is formed an elongated hole or opening 14, through which is inserted a washer or bushing 15, of a length slightly in excess of the thickness of the lever and provided with a central perforation. A bifurcated strap or stirrup 16, with coincident perforations in the legs, is slipped down over the lever until the several holes in the washer or bushing and in the legs of the stirrup are in line or register, when a pin 17 is passed through them and its ends riveted or flattened down, as shown. The stem-key proper is connected to the stirrup in any of the known ways.

By making the washer or bushing longer than the thickness of the lever and having it project slightly on each side thereof it will be seen that no precise work is required to properly rivet the pin, for no matter whether the blows upon the end of the pin be accidentally hard or unduly long continued there will not be any liability of bending the legs of the stirrup against the sides of the lever as heretofore.

To the outer end of the longer arm of lever 1 the connecting-rod C is attached through a substantially similar stirrup 18. This arm, like the longer arm of lever 2, is provided with an elongated slot and a perforated washer or bushing, and the legs of the stirrup are riveted in a manner similar to that just above described.

In all prior machines, so far as our knowledge extends, it has been customary to hang the connecting-rods C obliquely, with their lower ends nearer the center of the machine, and in order to raise the type-bars it has been necessary to pull these connecting-rods down in an oblique or inclined direction. There exists the objection to this mode of hanging and pulling the connecting-rods that the pivotal points or journals of the type-levers wear away quickly and unevenly, causing a looseness at the joint and a consequent imperfection of work.

We propose to hang the connecting-rods straight up and down and pull them in vertical lines, and we also propose connecting the stem-keys of the machine so that they shall work in right lines instead of obliquely or in arcs of circles, as heretofore.

By reason of the presence of the elongated holes 14 in the levers 1 and 2 we are permitted to effect these desiderata. In order to

prevent any lateral movement in either the stem-key or the connecting-rod, we secure a guide-plate G to the frame of the machine 70 and cause the lower ends of the parts mentioned to work through perforations therein, all as clearly shown. The stem-key, in addition to working through the guide-plate G, has a bearing also in a bridge-piece H, running transversely of the machine at the key-board.

Having now fully described the construction of a machine embodying our several improvements, we shall now briefly explain its 80 mode of operation.

Fig. 1, as will be readily observed, shows only one stem-key, compound lever, connecting-rod, and type-bar, and these parts are all illustrated in their normal positions of rest. 85 If the stem-key E be depressed, its shank will be guided in the perforations in the bridge-piece H and guide-plate G, and the longer arm of the lever 2 will be vibrated downwardly, during which the shorter arm of said lever will move upwardly, and, through the slot-and-pin connection, vibrate upwardly the shorter arm of lever 1 and depress the longer arm of said lever to the same extent as that to which the longer arm of lever 2 is vibrated. 90 During this movement of the levers the spring F will be bent backwardly, as illustrated at Fig. 2, and the connecting-rod C pulled down in a right line and the type-bar swung upwardly to make the desired impression upon 100 the paper of the platen, which is purposely omitted to avoid complicating the drawings. Immediately the power or force upon the stem-key is released the duplex spring F acts to return all the parts to their first positions, 105 as shown in Fig. 1.

In constructing a type-writing machine with our improved key-lever we propose to have separate standards 5 for the levers and set them upon the base-plate 7 in different localities, according to the bank of keys to which the levers are to be connected, and to have each corresponding arm of each compound lever exactly the same in length, so that all the levers shall have the same amount of depression and require the same amount of force to vibrate them and the type-bars, thus greatly improving the working of the machine. 115

Although we have shown only one means of connection between the shorter arms of the compound lever and only one form of spring for returning said levers to their normal positions, it will be understood, of course, that other means for making said connection and other forms of spring differently located 120 may be employed without departing from the main features of our invention.

What we claim as new, and desire to secure by Letters Patent, is—

1. In a type-writing machine, the combination of a stand, two connected levers fulcrumed on said stand and extending outwardly therefrom; a finger-key connected to one of said levers, a connecting-rod connected to the other 130

- of said levers, and a type-carrier adapted to be operated by the connecting-rod.
2. In a type-writing machine, the combination of a base-plate, a stand mounted thereon, two connected levers fulcrumed on said stand and extending outwardly, a spring, a finger-key, a connecting-rod, and a type-carrier.
3. In a type-writing machine, the combination, with a finger-key, connecting-rod, and type-carrier, of a compound lever pivoted or journaled in a stand secured to a base-plate at the bottom of the machine, and a spring for returning the moving parts, as and for the purpose set forth.
- 15 4. In a type-writing machine, the combination of a stem-key, a vertical rigid connecting-rod, a pivoted type-bar, levers 1 and 2, fulcrumed on a stand, the former having an elongated hole and the latter a pin engaging therewith, and a spring connected to the levers, as set forth.
5. In a type-writing machine, the combination, with a stem-key, connecting-rod, and type-bar, of a compound lever, and a duplex 25 spring connected to the said lever, as set forth.

6. In a type-writing machine, the combination, with a stem-key, connecting-rod, and type-bar, of a compound lever journaled or fulcrumed in a stand and a spring mounted in said stand and connected to said lever, as set forth.

7. In a type-writing machine, the combination, with a stem-key, connecting-rod, and type-carrier, of a compound lever consisting of the levers 1 and 2, the outer ends of the 35 longer arms of which are provided with elongated holes, the stirrups, the bridge-piece, and the guide-plate whereby the stem-key and the connecting-rod are required to reciprocate in vertical lines, as set forth.

In testimony that we claim the foregoing as our invention we have signed our names, in presence of two witnesses, this 8th day of December, 1886.
